UNITED STATES PATENT OFFICE.

MORTIMER JONES, OF FORT WORTH, TEXAS.

GAS BURNER.

Application filed July 11, 1927. Serial No. 204,885.

My invention relates to gas burners and more particularly to gas burners equipped with triple control means for controlling the inlet of gas and air to make the same co-ordinate with the outlet of explosive mixture through the mixing chamber or refractory.

A further object of the invention is to provide gas burners whereby the velocity of the gas is not changed when the volume thereof entering the mixing chamber of the burner is reduced, thereby insuring a satisfactory mixture of gas and air before the explosive mixture reaches the point of ignition, and to provide an adjustable outlet to the refractory or mixing chamber whereby a greater range of adjustment can be had.

Another object is to provide means for adjusting the outflow through the mixing chamber simultaneously with the adjusting of the intake of air and gas.

Another object is to provide control devices by which a uniform flame can be obtained regardless of volume.

This invention is an improvement on the burner shown in the patent granted to me May 11, 1926, No. 1,584,546.

Other objects and advantages will be fully explained in the following description and the invention will be more particularly pointed out in the claims.

Reference is had to the accompanying drawings which form a part of this application.

Fig. 1 is a longitudinal section of the burner, showing the chambers and the working devices within the chambers.

Fig. 3 is a front elevation of the refractory or mixing chamber.

Fig. 3 is a perspective view of the air-control devices.

Fig. 4 is an interior elevation of the gas control devices.

Fig. 5 is a rear elevation of the burner.

Fig. 6 is a front view of the mixing chamber, the shaft being shown in section.

Fig. 7 is a plan view of the air-receiving chamber, and the mixing chamber in section.

Fig. 8 is a vertical section of a refractory or discharge nozzle, showing a conical insert.

Fig. 9 is a front end view of the conical insert shown in Fig. 7.

Fig. 10 is a rear elevation of the same.

Similar characters of reference are used to indicate the same parts throughout the several views.

The drawings show a gas receiving or gas

inlet chamber 1 and an air receiving chamber 2 attached together. The chamber 2 is also a part of the air and gas mixing chamber. Gas is supplied to the chamber 1 through a pipe 3 which is provided with a control valve 4. A shaft 5 is journaled in the bearing 6 which is integral with the casing 1 and also journaled in a bearing 7 which is formed in the partitioned chamber 10. Gas is fed through a perforated disk 8 which is bolted rigidly to the casing 1. A control valve 9 is revolvably mounted on shaft 5 and bears against the disk 8. The disk 8 is provided with a plurality of perforations 11 and the valve 9 has a plurality of cut-off wings 12. More or less of the perforations 11 can be closed or opened by turning the shaft 5 which turns the valve 9 and wings 12. A spiral spring 13 is mounted on the shaft 5 and bears against the valve 9 and yielding washer 14. The valve 9 will be turned by the shaft 5 for opening or closing the perforations 12. The spring 13 will hold the valve wings 12 in close contact with the disk 8.

The feeding of the gas will be further controlled by the valve 4. A push rod 15 in two parts is actuated by a handle 16. When the shaft 5 is turned the handle 16 will actuate the push rod 15 to change the amount of gas which will pass through the valve 4. The valve 4 co-ordinates with the gas control valve 9 with its wings 12.

The chamber 2 is provided with air inlets 17 and an air-control valve 18 is attached to the shaft 5 and revolves with this shaft. The valve 18 is provided with air passages 19 and equal number of cut-offs 20. The valve 18 will be revolved with the shaft 5 for feeding more or less air to the chamber 2. The valve 18 co-ordinates with the gas feed valve 9, that is, the increase and decrease of the supply of air and gas is accomplished simultaneously. The amounts of gas and air can be changed when necessary. The valve 18 can be set at different positions on the shaft 5 and the disk 8 can be set at different positions relative the valve wings 12.

The explosive mixture is formed in the chambers 2 and 10. Means are provided for controlling the discharge of explosive mixture through the nozzle 21. A throttle valve 22 is pivotally mounted in the discharge nozzle 21 and may be held yieldingly down by a spring 23. A rest 24 is provided for the shaft 5 and a cam 25 is rigid with the shaft

5. When the shaft 5 is turned, the cam 22 will actuate the throttle valve 22. Thus the throttle valve 22 will be actuated to co-ordinate with the gas feed and the air feed. The opening and closing or partial opening and closing of the valve 22 affects the air and gas feed, that is, affects the volume of the air feed.

The variations shown in Figs. 7, 8 and 10 show a conical spreading device for the nozzle. A conical nozzle 26 is shown with wings 27 having curved tips 28. This form of spreader or muffler is simply forced into the end of the mixer.

15. The variation shown in Fig. 8 shows a spreader 29 which may be elevated more or less by the cam 30. A bearing 31 is provided for the shaft 5. The volume to be discharged will be varied as shown in Fig. 1.

20. Various other changes in the sizes, construction, proportion, and arrangement of the several parts may be made without departing from my invention.

What I claim is,—

25. 1. A gas burner comprising a combined air receiving and mixing chamber, a gas feeding chamber, gas control means consisting of revoluble valve in said gas feeding chamber and a stationary perforated valve in said air receiving chamber for feeding gas to said mixing chamber, a discharge nozzle, means in said discharge nozzle for varying the volume of explosive mixture, and a common shaft operatively connected to the gas feeding mechanism and to said explosive-mixture varying-means for simultaneously effecting the amount of gas to be fed and to vary the explosive mixture discharge.

40. 2. A gas burner comprising a combined air receiving and mixing chamber, a gas feeding chamber connected thereto, a gas control valve revoluble in said gas feeding chamber and a stationary perforated disk in said air receiving chamber for feeding gas to said mixing chamber, a revoluble air feed control means in said air-receiving chamber, a nozzle and an explosive mixture discharge control in said nozzle, and a shaft journaled in said burner and operatively connected to said gas feed control and to said air feed control and to said explosive mixture discharge control for actuating all controls simultaneously.

45. 3. A gas burner comprising a combined air receiving and mixing chamber, a gas feeding chamber connected thereto, a gas supply means for delivering gas to said gas feeding chamber and a gas supply control,

gas feed control means partly in said gas feeding chamber and partly in said air receiving chamber, an air feed control means in said air receiving chamber, a nozzle connected to said mixing chamber and an explosive mixture discharge control in said nozzle, and a shaft journaled in said burner and operatively connected to all of said controls for actuating the same simultaneously.

50. 4. A gas burner comprising a combined air receiving and mixing chamber, a gas feeding chamber connected thereto, a discharge nozzle connected to said mixing chamber, a gas feeding control consisting of a perforated disk in said air receiving chamber and a revoluble control valve in said gas feeding chamber adapted to open and close the perforations in said disk either all or part of said perforations, yielding means for pressing said valve against said disk, and a shaft journaled in said burner for revolving said control valve.

55. 5. A gas burner comprising a combined air receiving and mixing chamber, a gas feeding chamber connected thereto, a gas feeding control consisting of a perforated disk in said air receiving chamber and rigid therewith, and a revoluble control valve in said gas feeding chamber provided with wings for opening and closing or partly opening and partly closing the perforations in said disk, said air receiving chamber having inlet air ports, a cylindrical valve having ports in the periphery thereof adapted to register with the ports of said air-chamber, a discharge nozzle connected to said mixing chamber, and a shaft operatively connected to said valves for actuating both valves simultaneously.

60. 6. A gas burner comprising a combined air receiving and mixing chamber, a gas feeding chamber connected thereto, a gas feeding control for feeding gas to said mixing chamber, an air feed control for feeding air to said air receiving chamber, a nozzle connected to said mixing chamber, a pivoted control in said nozzle for varying the volume of discharge of explosive mixture, and a shaft journaled in said burner and operatively connected to said gas and air feed controls, and provided with a cam for actuating said nozzle discharge control and actuating all of said control elements simultaneously.

In testimony whereof, I set my hand, this 16th day of April, 1927.

MORTIMER JONES.
